COMBINED COUNTER, SINK, STORAGE AND
INDUCTION HEATING ELECTRIC COOKING
UNIT

Philip H. Peters, Jr., Greenwich, and John L. Matrone,
Schenectady, N.Y., assignors to Environmental/One
Corporation, Schenectady, N.Y.

Original design application Sept. 23, 1971, Ser. No.
183,289. Divided and this application Dec. 12,
1973, Ser. No. 424,106

Term of patent 14 years

Int. Cl. D6—04; D7—02; D23—02
U.S. Cl. D23—50

FIG. 1

FIG. 4

FIG. 5

FIG. 6

FIG. 1 is a perspective view from the top, front and one end of a combined counter, sink, storage and induction heating electric cooking unit showing our new design.

FIG. 2 is a top plan view thereof.

FIG. 3 is a front elevation thereof.

FIG. 4 is a rear elevation thereof.

FIG. 5 is an end elevation as seen from the left of FIG. 4.

FIG. 6 is an end elevation as seen from the right of FIG. 5.

This application is a division of my co-pending application Ser. No. 183,289, filed Sept. 23, 1971.

We claim:

The ornamental design for a combined counter, sink, storage and induction heating electric cooking unit, as shown.
